UNITED STATES PATENT OFFICE.

CHARLES CALLOWAY PRICE AND DOUGLASS VALENCIA BRIDWELL, OF DUMAS,
ARKANSAS.

STAND FOR FORD ENGINES.

1,373,526.

Specification of Letters Patent.

Patented Apr. 5, 1921.

Application filed November 26, 1919. Serial No. 340,870.

To all whom it may concern:

Be it known that we, CHARLES CALLOWAY PRICE and DOUGLASS VALENCIA BRIDWELL, citizens of the United States, and residents 5 of Dumas, in the county of Desha and State of Arkansas, have invented certain new and useful Improvements in Stands for Ford Engines, of which the following is a specification.

10 Our invention relates to stands for supporting internal combustion engines in convenient position for overhauling, and a purpose of our invention is the provision of a simple, compact and efficient stand of this 15 character which is designed to support two engines of the Ford type in such manner that the disassembling of one engine can be carried on without interfering with the disassembling of the other.

20 A further purpose of our invention is to provide a stand of this character which is adjustable to varying positions of the engines independently of each other so as to render any part of either engine accessible 25 for removal and repair.

We will describe one form of stand embodying our invention, and will then point out the novel features thereof in claims.

In the accompanying drawings:—

30 Figure 1 is a view, showing in side elevation one form of stand embodying our invention, with an engine in applied position thereon;

Fig. 2 is a view, showing in end elevation 35 the stand shown in Fig. 1;

Fig. 3 is a longitudinal sectional view of the supporting beam shown in the preceding views;

Fig. 4 is a perspective view of the stationary jaw of one of the supporting brackets; 40 and

Fig. 5 is a similar view of the movable jaw of one of the brackets.

Similar reference characters refer to similar parts in each of the several views.

Referring to the drawings, and particularly to Figs. 1 and 2, B designates a pair of base rails supporting intermediate their ends two pairs of standards S and S', such 50 rails and standards being formed in the present instance of piping and connected to each other by means of T-joints J. The opposite ends of the base rails B are provided with elbows L which are disposed in depending 55 relation to the rails, so as to form feet

for the same. The intermediate portions of the rails B are rigidly connected by brace rods R which have their opposite ends extending through the rails and joints J and secured thereto by means of nuts 14. As illustrated to advantage in Fig. 2, the standards of each pair of standards S and S' extend upwardly in converging relation to each other with their upper ends spaced apart and flattened, as at 15. The flattened 60 portions 15 are bent outwardly in opposite directions in the form of an arc to receive and support a clamping band 16. The flattened portions 15 are secured at suitable points to the band 16 by means of rivets 17, 65 the band being split and the ends turned outwardly to provide lips 16^a that are formed with registering openings to rotatably receive a screw threaded spindle 18. The spindle 18 is designed to effect a constricting of the band 16 and to this end one end of the spindle is provided with a crank 19 for rotating the same to effect a feeding of a nut 20, carried by the opposite end, in one direction or the other to move the lips 70 75 toward or away from each other and to thereby increase or decrease the diameter of the band. The band 16 for each pair of standards S and S' is adapted to receive a supporting beam generally designated at A 80 in a manner to allow rotation of the beam when the bands are extended and to securely lock the same against movement when the bands are constricted. As illustrated to 85 advantage in Fig. 3, the supporting beam A 90 comprises two sections 21 and 22 which are rotatably mounted upon a third section 23. All of the sections are of tubular formation with the sections 21 and 22 rotatably mounted upon the section 23 in a manner to permit a 95 circumferential adjustment of one section independently of the other. As shown in Fig. 3, a positioning of the inner section 23 with respect to the sections 21 and 22 is secured by tapering the outer ends of the sections 21 and 22, as indicated at 21^a and 22^a, 100 respectively, it being noted that the opposite ends of the inner surface abut the inner walls of the outer sections at the inner ends of the tapered portions. The outer ends of 105 the tapered portions 21^a and 22^a are open to receive dove-tailed heads 24^a formed on the inner ends of a pair of stationary jaws 24. The heads 24^a are secured within the tapered portions by means of rivets 25 and with the 110

inner walls of the portions snugly fitting the surface of the heads, the latter are securely held upon the sections.

The stationary jaws 24 constitute a part 5 of engine supporting brackets, and are formed on their inner edges with arcuate recesses 24^b, the walls of which are adapted to embrace a pair of cylinders of an engine. Partly embedded within each jaw at a point 10 between the recesses 24^b is a rod 26 having a T-shaped head 26^a formed at one end for securely retaining the rod within the jaw and screw threaded, as at 26^b at the other end. The rod 26 is adapted to support and 15 slidably receive a movable jaw 27 which, as illustrated to advantage in Fig. 5, is provided with an opening 27^a through which the rod 26 extends and a pair of spaced lugs 27^b which are adapted in the applied position of the bracket to engage the two center 20 exhaust ports of an engine. The threaded end 26^b of each rod 26 supports a nut 28, by virtue of which the movable jaw 27 can be 25 adjusted with respect to the stationary jaw 24 to receive and clamp an engine between the two.

Referring now to Fig. 1, E designates an engine of the Ford type which is shown in applied position upon one of the supporting 30 brackets, wherein the rod 26 is positioned between the two inner cylinders of the engine with the stationary jaw embracing one side of the cylinders and the movable jaw embracing the opposite side in such manner 35 that the lugs 27^b are disposed within the exhaust ports of the cylinders. It will be understood that in applying the engine to either of the brackets, the movable jaw 27 is first removed to allow of the insertion of the rod 40 26 between the two inner cylinders whereupon the jaw is replaced and forced into engagement with the cylinders by means of the nut 28.

Should it be desired to elevate one end or 45 the other of the engine E in order that certain parts of the engine may be accessible, it is obvious that by loosening the corresponding band 16 the corresponding section 21 or 22 can be rotated upon the inner section 23 any distance to effect the desired 50 adjustment of the engine, whereupon the band is constricted to again clamp the section and thereby secure the engine in this adjusted position. As the section 21 or 22 55 is capable of rotative adjustment independently of the other section, it is obvious that an engine carried by one bracket can be adjusted independently of the engine carried by the other bracket, and because of the disposition of the two brackets, it will be manifest 60 that an overhauling of the engine carried by one bracket can be carried on without interfering with the overhauling of the engine on the other bracket.

65 As shown in Figs. 1 and 2, the pairs of

standards S and S' are spanned intermediate their ends by a tool tray T, which is supported in horizontal position by U-bolts 29 which embrace the standards in the manner shown in the drawings. The tray T is provided with flanges 30 that constitute supporting guides for a pair of drawers 31.

From the foregoing description, taken in connection with the accompanying drawings, it will be manifest that we have provided a stand of simple and efficient construction which is capable of adjustably supporting a pair of engines, and that the adjustment of one engine can be effected independently of that of the other engine.

Although we have herein shown and described only one form of stand embodying our invention, it is to be understood that various changes and modifications may be resorted to without departing from the spirit of the invention and the spirit and scope of the appended claims.

Having thus described our invention, we claim:

1. A stand for supporting engines comprising, a frame, a beam comprising sections telescopically associated with each other, clamps carried by said frame and engaging certain of the sections for locking the same in adjusted positions, and adjustable brackets 90 carried by the clamp engaged sections.

2. A stand for supporting engines comprising a frame, a beam supported on the frame and comprising a pair of tubular sections, and a third section disposed within 100 and connecting the two sections in a manner to permit of the movement of one section independently of the other, engine supporting brackets carried by the first two sections, and means carried by said frame for locking the first two sections against movement.

3. A stand for supporting engines comprising a frame, a beam supported on the frame and comprising a pair of tubular sections, a third section disposed within and connecting the two sections in a manner to permit of the movement of one section independently of the other, engine supporting brackets carried by the first two sections, 110 split bands carried by said frame and embracing the first pair of sections, and manually operable means for constricting said bands to cause the same to clampingly engage said sections.

4. A stand for supporting engines comprising a frame, including base rails and two pairs of standards, with the standards of each pair disposed in converging relation to each other, a supporting beam comprising sections rotatable independently of each other, brackets carried by said sections, and clamping means formed on the upper ends of said standards for supporting and locking said sections against rotation.

5. A stand for supporting engines comprising a frame including base rails, two pairs of standards with the standards of each pair disposed in converging relation to each other, a tool tray supported on and between the pairs of standards, drawers supported by said tray, split bands carried by the upper ends of each pair of standards, a beam supported in said bands and comprising sections rotatable independently of each other, brackets carried by said sections, and screw threaded means for constricting said bands to lock said sections against rotation.
- 10 6. A stand for supporting engines comprising a frame including base rails and two pairs of standards, with the standards of each pair disposed in converging relation to each other, split bands secured to the upper ends of each pair of standards, a beam supported in the bands and comprising an inner
- section and a pair of outer sections rotatably mounted upon the inner section, brackets carried by the outer ends of the outer sections, and screw threaded means for constricting the bands to lock the outer sections 25 against rotation.
7. A stand for supporting engines comprising standards, clamping means secured to the upper ends of said standards, a beam supported by said means and comprising a 30 pair of sections rotatable independently of each other, brackets carried by the outer ends of said sections and each comprising a stationary jaw, secured to the corresponding section, rods carried by the jaw, a movable 35 jaw mounted on the rod, and a nut threadedly engaging said rod for effecting an adjustment of the movable jaw.

CHARLES CALLOWAY PRICE.
DOUGLASS VALENCIA BRIDWELL.
